DISPENSING CONTAINER

Carle C. Conway, Jr., Scarborough, N. Y., assignor
to Continental Can Company, Inc., New York,
N. Y., a corporation of New York

Application July 11, 1939, Serial No. 283,917

4 Claims. (Cl. 221—62)

The present invention relates to new and useful improvements in containers, and more particularly to improvements in a sheet metal dredging container for dispensing spices or the like materials.

The invention generally concerns a container having an end portion which is provided with an opening therethrough. A friction plug is provided for closing the opening in the container end and this plug is provided with sifting openings and with a pouring opening. A closure member in the form of a slide is mounted on the friction plug for sliding movement relative thereto, and this slide is adapted to move within pre-determined limits. In one position of the slide, the dispensing openings are covered and thus closed, and in other positions of the slide, the sifting openings or the pouring opening may be uncovered to permit the desired dispensing of the contents of the container.

An object of the present invention is to provide a container of the above type wherein the friction plug can be readily applied and removed from the container end and wherein a minimum amount of resistance is offered to movement of the sliding closure member.

A further object of the invention is to provide a container of the above type wherein the friction plug is formed from a single piece of metal having a flat top surface and a depending skirt adapted to frictionally engage with the opening in the container end and wherein lugs are provided for limiting movement of the friction plug into the container end so as to assure a free sliding connection between the closure member and the plug.

A still further object of the invention is to provide a container of the above type wherein the friction plug is provided with lateral projections forming trackways to which a sliding closure member is connected by means of flanges.

The invention still further aims to provide a container of the above type which is inexpensive to manufacture and which is of relatively simple construction.

The above and other objects of the invention will in part be obvious and will be hereinafter more fully pointed out.

50. In the accompanying drawing,

Figure 1 is a top plan view of the container showing the closure member covering the dispensing openings.

Figure 2 is a top plan view showing, in full lines, the closure member in position for permit-

ing dispensing of the contents through the sifting openings but closing the pouring opening.

Figure 3 is an enlarged sectional view taken along the line 3—3 of Figure 2.

Figure 4 is an enlarged sectional view taken along the line 4—4 of Figure 1.

Referring more in detail to the accompanying drawing, the container is illustrated as including a rectangular body portion 10, although it is to be clearly understood that the body portion may be of any desired shape. An end portion 11 is secured to the body portion by means of the usual double seam 12 or the like. The container end 11 is provided with an opening and the metal around this opening is bent downwardly 15 to form a depending friction wall 13.

The friction plug 14 is formed from a single piece of sheet metal and is provided with a depending peripheral skirt portion 15 which frictionally engages the friction wall 13 on the container end 11. The friction plug is substantially oblong in shape and the ends thereof are shaped by crimping or squeezing together the metal to provide outwardly extending lugs 16, 16a which engage the outer surface of the container end 11 and thus serve to limit the extent to which the friction plug can be forced into the opening in the container end. The top surface of the friction plug is disposed slightly above the surface of the container end 11 and is substantially flat. This top surface is provided with a group of sifting openings 17 and with a relatively large pouring opening 18. The sides of the friction plug 14 are shaped by crimping or squeezing together the metal to provide a plurality of laterally and outwardly extending lugs 19, 19a and the under surfaces of these lugs are spaced slightly above the upper surface of the container end 11, as particularly shown in Figure 4. The end lugs 16, 16a, as indicated above, serve to limit inward movement of the friction plug and thus maintain the under surface of the lugs 19, 19a spaced above the container end 11.

A closure member in the form of a slide 20 is connected to the friction plug 14 so that it will slide over the upper surface thereof. The closure member 20 is provided at the sides thereof with downwardly and inwardly curled edges 21, 21a which extend around and engage the under surface of the lugs 19, 19a, respectively. In this manner, the closure member 20 is mounted on the friction plug for sliding movement relative thereto. The ends of the closure member are curled to provide beads 22, 22a

50. 55. 45. 40. 35. 30. 25. 20. 15. 5. 55. 55.

which serve as finger grips for shifting the closure member between the limits of its movement. The flat top surface of the friction plug 14 is provided with upstanding lugs 23, 23a adjacent the ends thereof. These upstanding lugs serve as stops and are adapted to engage beads 22, 22a, respectively, on the closure member for limiting the sliding movement thereof.

As shown in Figure 1, the closing surface of the closure member 20 is dimensioned so that it will cover the sifting openings 17 and the pouring opening 18 when the closure member is disposed midway between the stop lugs 23, 23a. When the closure member 20 is shifted to the position shown in Figure 2 with the bead 22 abutting against the stop lug 23, the sifting openings 17 will be uncovered to permit sifting of the contents of the container but the pouring opening 18 will remain covered and closed. Similarly, when the closure member 20 is shifted in the opposite direction with the bead 22a abutting against the stop lug 23a, the pouring opening 18 will be uncovered and the sifting openings 17 will be covered and closed. The lugs 19, 19a on the friction plug 14 are spaced from one another, but this spacing is such that the depending curled flanges 21, 21a on the closure member 20 will always engage at least two of the lugs 19, 19a, respectively. This serves to prevent the closure member from being twisted relative to the friction plug.

From the foregoing description, it will be seen that the present invention provides a dispensing container wherein the lugs 19, 19a on the friction plug provide trackways with which the flanges 21, 21a on the closure member engage. The spaced lugs 19, 19a serve to reduce the frictional resistance offered to the sliding movement of the closure member 20. The lugs 16, 16a serve to limit inward movement of the friction plug relative to the container end 11 so as to maintain the under surfaces of the lugs 19, 19a spaced above the container end. It is to be further noted that the lugs on the friction plug 45 serve as a convenient means for permitting the use of a prying instrument to remove the entire friction plug when it is desired to remove the contents of the container by a spoon.

It is to be clearly understood that minor changes in the details of construction and arrangement of parts may be made without departing from the scope of the invention as set forth in the appended claims.

I claim:

- 55 1. A dispensing container comprising a body portion, an end secured to said body portion and having an opening therethrough with the metal surrounding the opening shaped to provide a friction wall, a friction plug fitting within and engaging the friction wall for closing the opening and having dispensing openings formed therein, said friction plug having the sides thereof shaped to provide a plurality of outwardly extending spaced lugs and having lugs 60 at the ends thereof engaging said container end to maintain the bottom surfaces of said spaced lugs disposed above the said container end, and a closure member having depending flanges at the sides thereof engaging said spaced lugs at 65 the sides of said friction plug and curled beneath the bottom surfaces thereof whereby to slidably connect the closure member to said friction plug, the spacing of said lugs at the sides of said friction plug and the length of said flanges being dimensioned so that the flanges on the closure member will 70
- 75 75

the closure member will always engage at least two of the lugs at the sides of said friction plug whereby to prevent twisting of the closure member relative to the friction plug.

2. A dispensing container comprising a body portion, an end secured to said body portion and having an opening therethrough with the metal surrounding the opening shaped to provide a friction wall, a friction plug fitting within and engaging the friction wall for closing the opening and having dispensing openings formed therein, said friction plug having the sides thereof shaped to provide a plurality of outwardly extending spaced lugs with the bottom surfaces of said lugs disposed above the said end, and a closure member having depending flanges at the sides thereof engaging said lugs and curled beneath the bottom surfaces thereof whereby to slidably connect the closure member to said friction plug, the spacing of said lugs and the length of said flanges being dimensioned so that the flanges on the closure member will always engage at least two of the lugs on said friction plug whereby to prevent twisting of the closure member relative to the friction plug. 25

3. A dispensing container comprising a body portion, an end secured to said body portion and having an opening therethrough with the metal surrounding the opening shaped to provide a friction wall, a friction plug fitting within and engaging the friction wall for closing the opening, and having sifting openings and a pouring opening formed therein, said friction plug having the sides thereof shaped to provide a plurality of outwardly extending spaced lugs with the bottom surfaces of said lugs disposed above the said end, and a closure member for controlling the dispensing openings and having depending flanges at the sides thereof engaging said lugs and curled beneath the bottom surfaces thereof whereby to slidably connect the closure member to said friction plug, the spacing of said lugs and the length of said flanges being dimensioned so that the flanges on the closure member will always engage at least two of the lugs on said friction plug whereby to prevent twisting of the closure member relative to the friction plug. 30

4. A dispensing container comprising a body portion, an end secured to said body portion and having an opening therethrough with the metal surrounding the opening shaped to provide a friction wall, a friction plug fitting within and engaging the friction wall for closing the opening, and having sifting openings and a pouring opening formed therein, said friction plug having the sides thereof shaped to provide a plurality of outwardly extending spaced lugs with the bottom surfaces of said lugs disposed above the said end, and a closure member for controlling the dispensing openings and having depending flanges at the sides thereof engaging said lugs and curled beneath the bottom surfaces thereof whereby to slidably connect the closure member to said friction plug, the spacing of said lugs and the length of said flanges being dimensioned so that the flanges on the closure member will always engage at least two of the lugs on said friction plug whereby to prevent twisting of the 40

closure member relative to the friction plug, said closure member being shaped so as to cover the sifting openings and the pouring opening in the intermediate position thereof and being adapted to uncover the sifting openings when shifted in one direction and being adapted to uncover

the pouring opening when shifted in another direction, and upstanding stop shoulders on said friction plug adjacent the ends thereof for limiting movement of said closure member in either direction.
